Primary Examiner — Justin C Dodson*Assistant Examiner* — Olivia B. El-Nemri*(74) Attorney, Agent, or Firm* — Carter, DeLuca & Farrell, LLP; George Likourezos; Bret P. Shapiro**CLAIM**

The ornamental design for a bottle as shown and described.

DESCRIPTION

FIG. 1 is a perspective view of a bottle showing our new design;

FIG. 2 is an elevational view of the front side;

FIG. 3 is an elevational view of the back side;

FIG. 4 is an elevational view of the left view;

FIG. 5 is an elevational view of the right view;

FIG. 6 is a top plan view thereof; and,

FIG. 7 is a bottom plan view thereof.

The broken lines shown in the drawings depict portions of the bottle that form no part of the claimed design.
